UNITED STATES PATENT OFFICE.

WILLIAM B. ENGLER, OF BALTIMORE, MARYLAND, ASSIGNOR TO GENERAL MOTORS CORPORATION, OF DETROIT, MICHIGAN, A CORPORATION OF DELAWARE.

DESIGN FOR A RADIATOR.

52,267.

Specification for Design.

Patented Aug. 20, 1918.

Application filed May 3, 1918. Serial No. 232,404. Term of patent 7 years.

To all whom it may concern:

Be it known that I, WILLIAM B. ENGLER, a citizen of the United States, and resident of Baltimore, in the county of Baltimore, in the State of Maryland, have invented a new, original, and ornamental Design for Radiators, of which the following is a specification, reference being had to the accompanying drawings, forming part hereof, and in which—

Figure 1 is a perspective view of a radiator built according to my design; and

Fig. 2 is a top plan view of the same.

I claim:

The ornamental design for a radiator, substantially as shown.

In testimony whereof I affix my signature.

WILLIAM B. ENGLER.
